UNITED STATES PATENT OFFICE.

FRANK W. FOPPOBY, OF LAWS, CALIFORNIA.

SUPERHEATER.

1,401,063.

Specification of Letters Patent. Patented Dec. 20, 1921.

Application filed October 29, 1918. Serial No. 260,124.

To all whom it may concern:

Be it known that I, FRANK W. FOPPOBY, a citizen of the United States, residing at Laws, in the county of Inyo and State of California, have invented new and useful Improvements in Superheaters, of which the following is a specification.

The object of the invention is to provide a super-heater construction for use in connection with locomotive, marine, stationary and other engines in which the super-heating elements or units are amply protected against the direct heat of the furnace or fire-box while being adapted to efficiently perform their intended function, and wherein the possibility of condensation within the super-heating elements or units is reduced to the minimum.

A further object of the invention is to provide an apparatus of this kind wherein the heating units are utilized to the best advantage so as to conserve the energy developed in the fire-box to the utmost, and at the same time to provide an apparatus which may be applied to a locomotive or other engine with the least possible alteration in the ordinary and approved designs of such engines.

Further objects and advantages will appear in the course of the following description, it being understood that changes in form, proportion and detailed arrangement may be resorted to, particularly in adjusting the apparatus to engines of different types, and within the scope of the appended claims, without departing from the spirit of the invention.

In the drawings:—

Figure 1 is a central longitudinal sectional view of an apparatus embodying the invention applied to a locomotive engine;

Fig. 2 is a transverse sectional view of the fire-box on the plane indicated by the line 2—2 of Fig. 1;

Fig. 3 is a longitudinal sectional view, partly broken away, of a modified construction wherein the lower longitudinal conductor is located outside of the boiler barrel;

Fig. 4 is a transverse sectional view on the plane indicated by the line 4—4 of Fig. 3;

Fig. 5 is a horizontal sectional view on the plane indicated by the line 5—5 of Fig. 1;

Fig. 6 is a view showing the construction and relation between the cut-off valve, lo-

cated in the smoke-box and the operating valve which is located in the cab when the apparatus is used in connection with a locomotive engine;

60

Fig. 7 is a detailed view showing the manner in which the tubes of the super-heating elements or units are embedded in the masonry or brick-work at the walls of the fire-box or combustion chamber;

65

Fig. 8 is a detailed view showing the joints between the extremities of the conductor tubes and the flue sheet;

65

Fig. 9 is a detailed view showing an efficient means whereby connection between a super-heater element or unit and a manifold may be effected;

70

Fig. 10 is an elevation showing the application of the super-heater apparatus to a stationary engine and indicating the water connection whereby the elements or units of the super-heater may be filled with water from the boiler, when starting the engine, so as to expedite the operation of raising steam.

80

Referring more particularly to the construction illustrated in Fig. 1, but applicable also in general features to that shown in Fig. 3, a conductor 20 is arranged in communication with the dome 21 of the boiler 22, and is connected within the smoke-box 23 with a depending pipe 24 which in turn is in communication by means of an elbow 25 with a longitudinal conductor 26 extending through the barrel of the boiler and in

85

turn is connected at its rear end with a manifold 27. In communication with this manifold are the terminals of the tubular elements or units 28, which may be looped back and forth any desired number of times, crossing the side and end walls of the fire-box or combustion chamber 29, and finally connected at their other terminals with a second manifold 30 which is located at the opposite side of the fire-box or combustion

90

chamber near the rear end of the boiler or in other words adjacent to the plane of the rear flue sheet and as in reference to the manifold 27 just in advance of the forward leg 31 of the boiler. The interior of the

95

fire-box or combustion chamber is provided as in the ordinary practice with a lining of fire-brick or similar refractory material 32 in which the manifold and super-heater elements or units are embedded as hereinafter

100

more fully explained while connected with the manifold 30, in a manner similar to that

105

Fig. 6 is a view showing the construction and relation between the cut-off valve, located in the smoke-box and the operating valve which is located in the cab when the apparatus is used in connection with a locomotive engine;

110

explained and shown with reference to the manifold 27 is a longitudinal conductor 33 extending forward to and communicating with the pipe 34 by which the super-heated steam is conveyed to the engine cylinders or other means by which the energy is utilized. Located in this conduit outlet or steam conductor is a cut-off valve 35, indicated in detail in Fig. 6 and hereinafter more fully described. Also in communication with the saturated steam pipe 24 and the super-heated steam pipe 33 are outlets 36 and 37 with which communication may be made by a circulating pipe, such as is ordinarily employed in connection with locomotives and leading into the cab for the purpose of supplying steam in the operation of the blower. The object in making the connection of the circulating pipe with the super-heating system in the manner indicated is to insure a circulation through the super-heating apparatus when steam is admitted to and from the circulating pipe, as when the engine is not working, and the cut-off valve 35 has been closed, so as to guard against the accumulation pressure and admission of same to the cylinders when the circulating system is used.

In the construction illustrated in Figs. 3 and 4 the super-heater is composed of the same elements as above described, the only essential difference in arrangement being that the main conductors 26^a and 33^a are located exteriorly of the barrel of the boiler instead of extending therethrough as shown and described with reference to the form illustrated in Figs. 1 and 2, but the construction of Fig. 1 is preferable under ordinary conditions for the reason that the risk of condensation due to cooling of the conductors is thereby minimized.

Preferably the conductors 26 and 33 extend through casing tubes 38 and 39 which are arranged longitudinally with reference to the boiler and in the construction illustrated in Figs. 1 and 2 are terminally attached to the flue sheet. In Fig. 8 there is illustrated a suitable means for mounting these casing tubes, the same embodying an interiorly threaded thimble 40 which is riveted to the inner surface of the rear flue sheet and has the rear end of the heating tube threaded thereinto, and a thimble 41 also interiorly threaded which is secured by bolts or rivets to the exterior surface of the front flue sheet, the opening of the front sheet being larger than that of the rear sheet so that the casing may be extended through the former in order to effect engagement with the latter. This method of mounting the casing tubes is desirable because of the difficulty of expanding tubes of required diameter to effect a water-tight joint with the flue sheet.

Also in Fig. 9 there is shown a conven-

ient means whereby the extremities of the super-heater elements or units may be connected with the manifolds, the latter having socket openings 42 in which are seated the extremities of said elements or units, clamping plates 43 engaging the elements and held in place by yokes or stirrups 44 engaged by nuts 45.

The refractory walls of the fire-box or combustion chamber are preferably constructed of bricks or blocks shown in detail in Fig. 7 having grooves or seats 46 formed therein preferably in the course of molding the same, and this arrangement serves not only to effectually protect the tubes from the direct heat of the interior of the furnace but prevents the destructive and disadvantageous jarring of the tubes or elements in the movement of the engine, and moreover said elements or units thereby constitute a means of keying the bricks or blocks constituting the wall, so that the elements or units of the super-heater and the units or elements of the refractory wall are mutually protective and the possibility of disarrangement of the parts or the fracture of the elements of the latter which would directly expose the tubes is reduced to the minimum.

The cut-off valve 35 which is preferably used in this connection to control the communication of the super-heated steam to the engine from the super-heating apparatus is indicated in detail in Fig. 6 and embodies the valve proper 47 to the stem 48 of which is connected a piston 49 operating in a cylinder 50, a valve opening spring 51 being located in the cylinder and exerting a normal tendency to open the valve. Connected with the cylinder of the cut-off valve, as also shown in Fig. 6, by means of a tube 52 is a cylinder 53 of an operating valve having a valve piston 54 provided with suitable packing rings 55. Also in communication with the cylinder of the operating valve is a feed pipe 56 leading from the boiler or in communication with the above mentioned circulating pipe so that when the valve piston 54 is in the position indicated in Fig. 6 the boiler pressure is communicated through the cylinder 53 and the tubes 52 to the piston in the cylinder 50 of the cut-off valve to maintain the latter in its closed position. Extending from the connecting tube 52 to the opposite end of the cylinder 53 is an exhaust by-pass 57, and communicating with the adjacent end of said cylinder 53 is an exhaust 58. Also in connection with the stem 59 of said valve piston is the throttle lever 60 with an interposed tension spring 61. When the engineer operates the lever to move the throttle rod locking said lever at the desired adjustment by means of the pawl and rack, he places the spring 61 under tension to gradually advance said valve piston 54. Obviously when said element has

advanced in one direction sufficiently to close the steam pipe 52 and open the exhaust, the cylinder 50 under the influence of the return spring 51 will discharge the pressure 5 in said cylinder 50 through the feed pipe 52 and by-pass 57 to the exhaust 58. It has been found in practice that an arrangement of this character is necessary in order to effect the proper operation of the cut-off 10 valve in view of the pressure due to the super-heating apparatus and the possibility of an accumulation of water of condensation.

In Fig. 10 there is illustrated a general 15 view of a stationary engine boiler having a super-heating apparatus substantially as hereinabove described including the manifolds 64, inlet and outlet conveyers 65 and 66 and super-heater elements or units 67, said 20 manifolds and heater elements being embedded in the refractory walls 68 of the furnace. In this construction it is found desirable to provide a water communicating pipe 69 having a suitable cut-off 70 extending 25 from the boiler 71 to one of the conductors leading to the manifold, so that in starting the furnace after a shut-down water may be permitted to enter the super-heater apparatus including the manifolds and connecting 30 elements or units as a means of more rapidly heating the contents of the boiler. When the proper temperature in the boiler has been attained, the water communicating pipe 69 may be cut off and the water drained 35 out of the super-heater apparatus so that the latter may perform its primary intended purpose of obtaining the saturated steam from the upper portion or dome of the boiler and converting it into super-heated steam by 40 passing from one conductor to the other through the super-heater elements or units embedded in the walls of the furnace or firebox.

From the foregoing description it will be 45 obvious that a super-heater apparatus of this type may be readily built into or applied to an engine or boiler construction already in use without materially affecting the ordinary construction and arrangement of 50 the parts. In fact in so far as stationary en-

gines are concerned, no change whatsoever in the essential parts thereof is necessary. In so far as a locomotive engine is concerned the only changes involve the introduction of the conductors and the positioning of the 55 manifolds and the super-heater elements or units in the specially prepared refractory walls, bricks or blocks.

Having thus described the invention what is claimed is:—

1. In combination with a locomotive engine boiler, a super-heating apparatus comprising receiving and discharging manifolds and connecting elements, or units, located within the fire-box or combustion 65 chamber, saturated and super-heated steam conductors in communication respectively with said manifold and also in communication respectively with the steam dome of the boiler and the steam supply pipe, 70 and extending longitudinally of and through the boiler incasing tubes surrounding the portions of said conductors within the boiler and terminally attached to and supported by the forward and rear flue 75 sheets, said tubes being terminally threaded exteriorly, and tubular interior sockets attached respectively to said forward and rear flue sheets and having their flanges secured respectively to the inner and outer 80 surfaces of said sheets.

2. In combination with an engine having a boiler and terminally arranged smoke-box and fire-box, a super-heating apparatus having manifolds arranged within the fire-box 85 and respectively in communication with the steam space of the boiler and the steam supply pipe, super-heater elements or units connecting said manifolds and disposed adjacent to the walls of said fire-box, and a refractory fire-box lining consisting of bricks or blocks disposed in the planes of said elements or units and having registering seats for the reception thereof whereby the elements or units are embedded in the lining 95 and the bricks or blocks of the latter are keyed by the elements or units of the super-heater.

In testimony whereof I affix my signature.

FRANK W. FOPPOBY.
